DESIGN FOR A CRIBBAGE BOARD

James W. England, Jr., Prescott, Ariz.

Application November 27, 1944, Serial No. 116,566

Term of patent 14 years

(CL. D34—5)

To all whom it may concern:

Be it known that I, James W. England, Jr., a citizen of the United States and resident of the city of Prescott, county of Yavapai, State of Arizona, have invented a new, original, and ornamental Design for Cribbage Board, of which the following is a specification, reference being had to the accompanying drawing forming a part thereof, in which:

Fig. 1 is a top plan view of a cribbage board, showing my new design;

Fig. 2 is a bottom plan view; and

Fig. 3 is a side elevation.

I claim:

The ornamental design for a cribbage board, substantially as shown.

JAMES W. ENGLAND, JR.
